INVENTOR
JOHN BAILLIE
BY his ATTORNEY
Mr. Wallace White

UNITED STATES PATENT OFFICE.

JOHN BAILLIE, OF PIETERMARITZBURG, NATAL, SOUTH AFRICA.

AUXILIARY AIR-VALVE.

1,320,441.

Specification of Letters Patent.

Patented Nov. 4, 1919.

Application filed March 27, 1918. Serial No. 225,117.

To all whom it may concern:

Be it known that I, JOHN BAILLIE, a subject of the King of Great Britain, residing at Pietermaritzburg, Province of Natal, 5 South Africa, have invented new and useful Improvements in Auxiliary Air-Valves for Internal-Combustion Engines, of which the following is the specification:

In the air valves at present in use on 10 motor cars and such like vehicles I find that the air is invariably drawn into the cylinders through one side of the induction pipe only, the air so drawn in having a tendency to creep along the side of the pipe without 15 being completely incorporated with the gasoline mixture drawn from the carburetor to the cylinders, and this is one of the causes of backfiring and uneven running during speed variations.

20 By the use of my improved air valve the air is admitted simultaneously from both sides of the induction pipe and is sprayed through the perforations inside the induction pipe right into the gasoline mixture 25 which is at the same time being drawn from the carburetor and passed into the cylinders as a completely incorporated explosive mixture resulting in increased power and a considerable reduction in gasoline consumption; 30 while at the same time the faults above referred to are eliminated.

My invention consists of a perforated metal tube being thicker in one part than the other. I describe the thicker part as the 35 base and the thinner part as the stem, which latter is open at its outer end. Within the tube is inclosed a double plunger, the large head of which is seated in the base of the tube, while the smaller head projects into the 40 stem of the tube. When not in operation the plunger is retained in position by a spiral spring contained within the base of the tube. At the end of the base of the tube is a screw cap having a hole in the center 45 to admit the control wire which is attached to the head of the plunger.

The tube and plunger may be constructed of steel, brass or any suitable metal.

In the accompanying drawings which represent 50 different views of my invention:

Figure 1 is a view showing in side elevation one form of air valve embodying my invention. Fig. 2 is a longitudinal sectional view of the valve shown in Fig. 1. Fig. 3 5 is a sectional view of the induction or intake

manifold having applied thereto the valve shown in the preceding views.

There are from four to six perforations in the base and from twelve to twenty four perforations in the stem. 60

The control wire and covering is shown projecting through the cap of the base and the nut for securing the valve to the induction pipe is shown at the other or outer end of the stem. In practice I find that the 65 number and size of the perforations may be varied and the size of the air valve would necessarily be modified according to the size and capacity of the engine.

The action of the plunger is controlled by 70 the control wire A which is operated from the steering column by lever as in ordinary practice or from the dash by a knob, or it may be operated automatically by being connected to the throttle control system—or in 75 any other convenient manner.

When in operation the plunger is drawn up toward the cap C which results in the uncovering of the perforations near the thin end of stem of the tube (the outer end of which as already mentioned is open) as well as those of the thick end or base, thus admitting air at both ends, which air is drawn through the perforations or holes within the induction pipe and is uniformly distributed, 80 with the result that the air is thoroughly incorporated with the gasoline mixture being drawn from the carburetor and passed into the cylinders as a thoroughly incorporated mixture. 85

Having now particularly described and ascertained the nature of my said invention and in what manner the same is to be performed, I declare that what I claim is:

1. A device of the class described comprising a body having a perforated base portion and a perforated stem portion of a diameter less than the base portion, said stem portion being adapted to extend transversely through the intake manifold of a gas engine 100 and having its outer end open, and slidale means within the body for controlling said perforations. 95

2. A device of the class described comprising a tubular body having a perforated base 105 portion and a perforated stem portion of a diameter less than the base portion, said stem portion being adapted to extend transversely through the intake manifold of a gas engine and having its outer end open and 110

disposed exteriorly of the manifold, rigidly connected plungers movable in said portions, means for forcing the plungers to one end of the portions, and manually operable means for moving said plungers against the action of said forcing means.

Dated at Pietermaritzburg, Province of Natal, South Africa, this 10th day of January, 1918.

J. BAILLIE.

Witness:

W. M. MASTERSON.
